UNITED STATES PATENT OFFICE.

WILLIAM F. MICHAEL, OF PHILADELPHIA, PENNSYLVANIA, ASSIGNOR TO
BAILEY, BANKS & RIDDLE, OF SAME PLACE.

DESIGN FOR A SPOON.

SPECIFICATION forming part of Design No. 20,990, dated August 11, 1891.

Application filed July 9, 1891. Serial No. 398,979. Term of patent 3½ years.

To all whom it may concern:

Be it known that I, WILLIAM F. MICHAEL, a citizen of the United States, residing in the city and county of Philadelphia, State of Pennsylvania, have invented and produced a new and original Design for a Spoon, of which the following is a specification, reference being had to the accompanying drawing, forming part thereof.

10 The leading feature of my design for a spoon is a handle having a shank with the representation of a musket and sword thereon, and a tip with the representation of a grouping of canteens thereon, and busts of person-

15 ages on the canteens.

In the drawing, A designates the handle

of a spoon. On the shank thereof is the representation of a musket B and sword C. Near the tip of the handle is the representation of a scroll D, on which are the names "Grant, 20 Sherman and Sheridan." On the shank is a wreath E. On the tip is the representation of a grouping of canteens F, having on the faces thereof, respectively, the busts of Generals Grant, Sherman, and Sheridan. 25

I claim—

A design for a spoon, as shown and described.

WILLIAM F. MICHAEL.
